UNITED STATES PATENT OFFICE

126,285

DESIGN FOR A TEXTILE FABRIC OR SIMILAR ARTICLE

Julia Morris, New York, N. Y., assignor to Cohn
Hall Marx Co., New York, N. Y.

Application February 24, 1941, Serial No. 99,186

Term of patent 3½ years

To all whom it may concern:

Be it known that I, Julia Morris, a citizen of the United States of America, residing at 75 Central Park West, New York, in the county and State of New York, have invented a new, original, and ornamental Design for a Textile Fabric or Similar Article, of which the following is a specification, reference being had to the accompanying drawing, forming a part thereof.

The figure is a plan view of a textile fabric showing the complete width of my new design. The dot and dash lines on the drawing outline substantially the design unit, which unit is repeated in regular succession as indicated by the extensions beyond the unit boundaries.

I claim:

The ornamental design for a textile fabric or similar article, as shown and described.

JULIA MORRIS.
